UNITED STATES PATENT OFFICE.

CHARLES B. MILLS, OF GARDENVILLE, MARYLAND, ASSIGNOR OF ONE-FOURTH TO
ALFRED J. CARE, OF BALTIMORE, MARYLAND.

CABLE-CONNECTOR.

1,144,225.

Specification of Letters Patent. Patented June 22, 1915.

Application filed September 24, 1913, Serial No. 791,633. Renewed March 16, 1915. Serial No. 14,752.

To all whom it may concern:

Be it known that I, CHARLES B. MILLS, a subject of the King of Great Britain, residing at Valley View avenue, Gardenville, in 5 the State of Maryland, have invented new and useful Improvements in Cable-Connectors, of which the following is a specification.

This invention relates to improvements in 10 cable connectors and has particular application to a device of this class whereby the adjacent ends of cable sections may be rapidly and effectively joined or connected.

In carrying out the present invention, it 15 is my purpose to provide a cable connector which will be constructed in such manner that the ends of the cable sections will be effectively and efficiently connected or joined without resorting to the use of tape and the 20 like.

It is also my purpose to provide a connector of the class described which will embody 25 companion sections so formed that any one section of cable may be connected to any other section without changing the connector sections at the ends thereof, thereby providing a connector which is universal in practice.

Furthermore, I aim to provide a connector 30 which will embrace the desired features of simplicity, efficiency and durability, one which may be manufactured and marketed at a small cost and one which may be installed at a minimum expense.

35 With the above and other objects in view, the invention consists in the construction, combination and arrangement of parts hereinafter set forth in and falling within the scope of the claims.

40 In the accompanying drawing: Figure 1 is a top plan view of a connector constructed in accordance with my present invention, the same being shown as applied to the meeting ends of cable sections. Fig. 2 is a longitudinal sectional view on the line 2—2 of Fig. 1. Fig. 3 is a view in side elevation of the connector, and Fig. 4 is a sectional view on the line 4—4 of Fig. 3.

Referring now to the accompanying drawing in detail, the numerals 1, 1 designate the

adjacent ends of two cable sections, such sections being of the duplex type and each embodying two parallel conductors 2, 2.

My improved connector comprises companion sections 3, 3 each comprising a substantially rectangular block 4 composed of some suitable insulating material and formed with longitudinally extending parallel bores 5, 5 opening onto one end of the block and seated within the bores 5, 5 are metal plugs 6 of good conducting material having the ends thereof contiguous the open ends of the bores formed with sockets 7 each receiving the adjacent end of the respective conductor 2 and sweated or otherwise fixed thereto.

The outer end of each block 4 is rabbeted as at 8 and the respective ends of the plugs 6 are similarly formed so that a substantially flat surface is provided. By means of this construction, it will be seen that the 70 rabbeted end of one block will seat within the similar portion of the other block forming the connector so that when the sections are assembled in connector formation substantially flush surfaces are provided.

The rabbeted portion of each section composed of the block and plugs is formed with transverse bolt holes 9 aligning with similar interiorly threaded holes 10 formed in the other sections and designed to receive bolts 80 11 whereby the sections of the connector are secured together.

From the foregoing description taken in connection with the accompanying drawing, the construction, mode of operation and manner of employing my invention will be readily apparent. It will be seen that I have provided a cable connector wherein the companion sections each has one end fastened to the respective cable end and the opposite 90 end rabbeted and seated within the rabbeted portion of the other section thereby providing flat surfaces and enabling the sections of the cable to be readily and securely fastened in cable formation.

I claim:

A cable connector comprising companion sections each formed of a block of insulating material having longitudinal bores formed therein and spaced apart in parallelism, 100

plugs disposed within said bores and each having one end thereof formed with a socket receiving the adjacent end of the conductor of the cable, the free end of each block and the adjacent extremities of said plugs being rabbeted and adapted to seat upon the rabbeted end of the other section and bolts passed through the rabbeted ends of said

sections and having the head thereof counter-sunk within the sections.

In testimony whereof I affix my signature in presence of two witnesses.

CHARLES B. MILLS.
